UNITED STATES PATENT OFFICE.

JAMES WATSON GIEVE, OF LONDON, ENGLAND, ASSIGNOR TO GIEVE, MATTHEWS &
SEAGROVE LIMITED, OF PORTSMOUTH, ENGLAND.

LIFE-SAVING WAISTCOAT.

1,143,899.

Specification of Letters Patent. Patented June 22, 1915.

Application filed February 5, 1915. Serial No. 6,369.

To all whom it may concern:

Be it known that I, JAMES WATSON GIEVE, a subject of the King of Great Britain, residing at 65 South Molton street, in the county of London, England, have invented new and useful Improvements in and Relating to Life-Saving Waistcoats, of which the following is a specification.

My invention relates to improvements in life-saving garment.

My invention is designed to provide a life-saving garment of serge or other suitable material for use as an ordinary seaman's waistcoat under normal circumstances, but a portion of said waistcoat being capable of being blown out into an air ring under the arms of the wearer to form a life-saving jacket, in moments of emergency.

My invention is illustrated by way of example in the accompanying drawings, in which:

Figure 1 shows a front view of the waistcoat. Fig. 2 shows a back view. Fig. 3 shows a front view with the air ring expanded, and Fig. 4 shows an enlarged view of the waistcoat opened out in a flat position.

Referring now to the drawings, I provide an extra piece of material 1, of which the waistcoat 2 is made, sewn or otherwise attached to the waistcoat in a suitable position under the arms as shown in the drawings. The said extra piece of material 1 extends completely around the waistcoat in approximately the same horizontal plane. The said piece of material 1 is adapted to form a cover for a rubber tube 3 shown in Fig. 4, adapted when blown out to conform to the same form as said piece of material 1, so that when said tube is expanded, a hoop-shaped bladder entirely surrounding the person wearing the waistcoat is formed as shown in Fig. 3, in that position of the body in which it is most desirable to support the seaman in a position in which he is upright in the water or preferably with the upper portion of his body and head thrown

backward. The mouthpiece 4 of said tube 3 is provided with a valve 5 enabling the wearer of the waistcoat to blow up the tube at any desired moment without difficulty. Hook and press fasteners are provided whereby the extra piece of material containing the tube lies in a flat position against the waistcoat under ordinary circumstances as shown in Figs. 1 and 2.

In order to insure that the head of the wearer is thrown backward so that the wearer's mouth is clear of the water even in heavy weather, I prefer to arrange the tube 3 in such proportions that its larger portion extends around the chest of the wearer.

What I claim is:

1. A life-saving garment in the form of a waistcoat comprising an extra piece of material surrounding and attached to the waistcoat under the arm holes, fastenings adapted to connect the ends of said piece of material, an air tube inclosed in said extra piece of material, an inflating tube projecting from said air tube through a pocket of the waistcoat and a valve at the free end of said inflating tube.

2. A life-saving garment in the form of a waistcoat comprising an extra piece of material surrounding and attached to the waistcoat under the arm holes, an air tube inclosed in said extra piece of material, so proportioned that its larger portion extends around the front of the waistcoat, fastenings for connecting the ends of said piece of material, an inflating tube projecting through said tube through a pocket of the waistcoat and a valve at the free end of said inflating tube.

In testimony whereof I have signed my name to this specification in the presence of two subscribing witnesses.

JAMES WATSON GIEVE.
